UNITED STATES PATENT OFFICE.

JOSEPH BYERS, OF NEWTONVILLE, AND GEORGE TAYLOR, OF EVERETT,
MASSACHUSETTS.

AUTOMATIC ELEVATOR-HATCHWAY GUARD.

SPECIFICATION forming part of Letters Patent No. 276,767, dated May 1, 1883.

Application filed August 24, 1882. (No model.)

To all whom it may concern:

Be it known that we, JOSEPH BYERS, of Newtonville, in the county of Middlesex and State of Massachusetts, and GEORGE TAYLOR, of Everett, in the county of Middlesex and State of Massachusetts, have invented a new and Improved Automatic Elevator-Hatchway Guard, of which the following is a full, clear, and exact description.

This invention relates to an improvement in automatic elevator-hatchway guards; and it consists in the combination and arrangement of parts, substantially as hereinafter more fully set forth and claimed.

Reference is to be had to the accompanying drawings, forming part of this specification, in which similar letters of reference indicate corresponding parts in both the figures.

Figure 1 is a perspective view of an automatic guard attachment with our improvement applied thereto. Fig. 2 is a section of the fixed spring gripping jaws to receive and hold the swinging guard.

In order to explain the operation and show the application of our invention, we will first describe an automatic hatchway-guard and its connection to an elevator, which is as follows:

a is a rack-bar adapted to be supported upon one of two posts or standards, c, each of said standards also having a rack, as is usual in elevators of the class to which our improvement is applicable. This bar or rack has a frictional roll, g, against which strikes the cam-

bar d of the ascending or descending carriage or platform, which causes the said rack to operate a pinion, e, on a shaft, f, bearing upon the standard v, and to which shaft is secured the guard h, whereby the latter is raised or lowered with the movement of the elevator carriage or platform, according as the upper or lower inclined end of the cam-bar d is brought into contact with the frictional roll of the rack a. The holding device of the opposite end of the guard h, which embodies our improvement, is of the following construction:

k is a pivoted or articulated jaw connected to a fixed jaw, j, of the stand i, both of which jaws are faced with rubber or other elastic cushions l l to prevent concussion when the guard falls. A spring, n, having one end connected to the stand i and its other end adapted to act on the jaw k, causes the latter jaw, k, to catch the free end of the guard and prevent it from rebounding as it falls.

Having thus fully described our invention, we claim as new and desire to secure by Letters Patent—

The combination of a spring-pressed gripping-jaw, k, with the jaw j, stand i, and the swinging guard h, substantially as described.

JOSEPH BYERS.
GEORGE TAYLOR.
